(57) **CLAIM**

The ornamental design for a low profile pneumatic walking brace, as shown and described.

DESCRIPTION

FIG. 1 is a perspective view of the low profile pneumatic walking brace of the invention;

FIG. 2 is a left view of the walking brace of FIG. 1;

FIG. 3 is a right view of the walking brace of FIG. 1;

FIG. 4 is a front view of the walking brace of FIG. 1;

FIG. 5 is a rear view of the walking brace of FIG. 1;

FIG. 6 is a bottom view of the walking brace of FIG. 1; and,

FIG. 7 is a top view of the walking brace of FIG. 1.
